(74) Attorney, Agent, or Firm: Laurence A. Greenberg; Werner H. Stemer; Ralph E. Locher

(57) CLAIM

The ornamental design for a dispenser, as shown and described.

DESCRIPTION

FIG. 1 is a front perspective view of a dispenser;

FIG. 2 is a front elevation view thereof;

FIG. 3 is a right side elevation view thereof;

FIG. 4 is a left side elevation view thereof; and,

FIG. 5 is a top plan view thereof.

The broken lines show portions of the dispenser that form no part of the claimed design.

1 Claim, 5 Drawing Sheets
